(57) **CLAIM**

The ornamental design for a cream and deodorant dispenser container, as shown and described.

DESCRIPTION

The present invention is related to co-pending Design Applications Ser. Nos. 29,113,784, and 29,113,785, all entitled "Cream and Deodorant Dispenser Container", filed here-with.

FIG. 1 is a perspective view of the cream and deodorant dispenser container looking toward the front, top and right side, showing my new design;

FIG. 2 is a front elevational view thereof;

FIG. 3 is a right side elevational view thereof;

FIG. 4 is a top plan view thereof;

FIG. 5 is a back elevational view thereof;

FIG. 6 is a left side elevational view thereof;

FIG. 7 is a bottom plan view thereof;

FIG. 8 is a perspective view of FIG. 1 thereof, with the cap removed for clarity of illustration;

FIG. 9 is a top plan view of FIG. 8;

FIG. 10 is a perspective view of a second embodiment of FIG. 1 thereof, with the cap removed for clarity of illustration; and,

FIG. 11 is a top plan view of FIG. 10.
